UNITED STATES PATENT OFFICE.

DOMINGO A. PISTORIO, OF WASHINGTON, DISTRICT OF COLUMBIA.

FUSE.

1,383,777.

Specification of Letters Patent. Patented Mar. 16, 1920.

Application filed October 1, 1915. Serial No. 53,590.

To all whom it may concern:

Be it known that I, DOMINGO A. PISTORIO, a citizen of the United States of America, and resident of Washington, in the District 5 of Columbia, have invented certain new and useful Improvements in Fuses, of which the following is a specification.

This invention relates to ordnance and particularly to firing pins for projectiles 10 adapted to operate when the projectile strikes an object.

An object of this invention is to provide novel means for retaining the firing pin of a projectile in inoperative position or at a 15 safety position, which will prevent its movement with relation to the fulminating cap with which it coacts to fire the charge, novel means being also provided for releasing the said firing pin to permit its operation upon 20 impact of the projectile and the movement of the hammer or plunger, due to such impact.

A still further object of this invention is to provide means for guarding the firing 25 pin against movement, said guarding means being operated by centrifugal force when the projectile is in motion after being fired from a gun so that the said firing pin may move toward the fulminating cap under the 30 influence of a spring, such provision being made so that when the centrifugal force has operated to release the firing pin, it may be retained in released position until the projectile hits.

35 A still further object of this invention is to provide means for adjusting the position of the fulminating cap with relation to the firing pin and to retain the said cap in proper relation to the firing pin.

40 Furthermore, an object of this invention is to provide means for igniting the explosive charge of a projectile and for so timing it that the ignition will be delayed a predetermined time after the said projectile has 45 struck an object, the purpose being to permit the projectile to penetrate the object to insure the explosion of the projectile on the inside rather than on the outside of the mark.

50 A still further object of this invention is to produce a fuse for a projectile which will prove positive in its operation under all service conditions, especially so with respect to those parts which will release the firing 55 pin and cause it to move initially to insure

its operation when struck by the plunger or hammer and the means for retaining it in its released position, even though the rotation of the projectile decreases until the operation of the centrifugally operated releasing devices are uninfluenced by centrifugal force. 60

With the foregoing and other objects in view, the invention consists in the details of construction, and in the arrangement and 65 combination of parts to be hereinafter more fully set forth and claimed.

In describing the invention in detail, reference will be had to the accompanying drawings forming part of this specification 70 wherein like characters denote corresponding parts in the several views, and in which—

Figure 1 illustrates a longitudinal sectional view of a fuse casing with the parts 75 for firing the fuse partly in elevation and partly in section therein;

Fig. 2 illustrates a longitudinal sectional view at a position at right angles to that shown in Fig. 1; 80

Fig. 3 illustrates a sectional view on the line 3—3 of Fig. 1;

Fig. 4 illustrates a sectional view on the line 4—4 of Fig. 1;

Fig. 5 illustrates a sectional view on the 85 line 5—5 of Fig. 1;

Fig. 6 illustrates a sectional view on the line 6—6 of Fig. 1;

Fig. 7 illustrates a longitudinal sectional view showing means for delaying the firing 90 of the projectile;

Fig. 8 illustrates a face view of the cap holder;

Fig. 9 illustrates a sectional view showing the cap and holder in a slightly modified 95 form;

Fig. 10 illustrates a fragment of the firing pin and guards in different positions as compared with the illustration in Fig. 1;

Fig. 11 illustrates a sectional view of the 100 fuse, embracing a modified construction with the firing pin in position just before the hammer operates the pin;

Fig. 12 illustrates a sectional view on the line 12—12 of Fig. 11; 105

Fig. 13 illustrates a sectional view on the line 12—12 of Fig. 11 with parts in different adjustments;

Fig. 14 illustrates a view in elevation of a 110 face plate.

In these drawings 11 denotes the fuse casing which is externally threaded as is ordinarily done with fuse casing of this type. Internally, the fuse case has a bore which 5 is different in diameter at several points throughout its length forming shoulders 12 and 13 for purposes to be presently explained. The casing is furthermore internally threaded as at 14, the said threads extending from the end to a point intermediate its length and they are provided for engaging the retaining ring nut 15, which ring nut is operative to hold parts of the device 10 assembled. Within that portion of the bore 15 of the casing having the smallest diameter is a plunger or hammer 16 which is adapted to move longitudinally of the casing upon impact of the projectile and in order to insure free movement of this hammer or plunger 20 16 (which element will be hereinafter referred to as a hammer) it is grooved longitudinally as shown at 17 so that as it travels in the casing, air may pass through these grooves and prevent cushioning of the 25 hammer.

The firing pin comprises a head 18 which is struck by the hammer, a stem 19 and a body 20 from which the pins 21 project, it being understood that the number of firing 30 pins may be increased or diminished according to requirements and for the purpose of illustration, three firing pins are here shown. Intermediate the length of the body, there is a shoulder 22 forming an abutment for 35 a spring 23 which encircles a portion of the body and has a bearing on the shoulder 24 formed in the housing 25 for the firing pin.

In the construction of the housing for the 40 firing pin, a plate 25 is secured to one end of the said housing and the said plate has an aperture 26 in which the head is slideable and in which it is guided, the said plate being secured to the housing by fastenings 45 such as screws 26'. The housing is furthermore provided with a radially extending channel 27 in which cups 28 are stationed, the said cups being held in place by a sleeve 29 which encircles a portion of the housing 50 of the firing pin, as fully shown in the drawing.

Within the radial channel there are guards 30, here shown as having central recesses 31 to receive the cups 28 so that the said guards 55 may move outwardly with relation to the cups and telescope them when centrifugal force, due to the rotation of the projectile acts to impart movement to the said guards.

The guards are, however, held near the center of the casing by springs 32 seated in the cups and in the recesses of the guards, but the tension of these springs is readily overcome by the centrifugal force and they, therefore, move outward and clear the 65 shoulder of the head 18 to permit the spring

23 to move the said head longitudinally of the casing in the path of travel of the guards should said guards have a tendency to return to their normal positions by reason of discontinuance of the exercise of the centrifugal force. If the said guards move inwardly under the influence of the springs, they would engage side surfaces of the head and would be held in that position until the firing pin has been actuated to strike the cap. 70 In order to insure free movement of the guards, each has an aperture 33 so that air may pass therethrough to prevent cushioning of the said guards, and the faces of the said guards are concaved as shown at 34 80 to form seats for the shank of the firing pin and to insure clearance of the head of the firing pin.

The cap sockets 35 are formed in a plate 36 secured within the casing by the ring nut 85 15, which ring nut bears against one side near its edge and holds it in intermediate relation with the housing of the firing pin. The plate has apertures 37 which extend through the said plate and merge with the 90 cap sockets and the inner face of the said plate 36 has an angular seat 38 in which a disk 39 is held, the said disk 39 serving to retain the caps in their sockets. The disk is held between the plate 36 and the housing 95 of the firing pin and it may be penetrated by the spurs of the firing pin.

In order to insure proper positioning of the caps with relation to the spurs of the firing pin, the plate 36 has ribs 41 on one of its faces, which lie in slots or recesses 42 formed in the outer face of the firing pin housing.

A modification of the cap holding plate is shown in Fig. 9, the same comprising a 105 plate 45 having threaded apertures 46 in which apertured plugs 47 are threaded, the apertures being designed for the reception of shanks of the caps 48 and the said apertures form ways through which the flame reaches the charge. The plate 45 is in other respects of the same construction as the plate 36 and further detailed description thereof is believed to be unnecessary.

The inner end of the fuse casing is provided with a disk or plate 49 which holds the explosive 50, which is ignited by the caps, it being understood that the charge 50 is utilized for igniting the charge contained in the projectile. 115

As a means for delaying the ignition of the explosive in the projectile, the device shown in Fig. 7 is employed, the same comprising a casing 51 threaded as at 52 to enter the projectile and it is the purpose of 125 the inventor that this casing 51 be made of such appropriate length as to increase or diminish the time between the impact of the projectile and the firing of the charge. The casing may, therefore, be made to extend 130

a greater or less distance into the projectile as the requirements of practice may demand and the inventor does not wish to be limited with respect to these proportions.

5 In the modified construction, the plate 53 which carries the cap 57 is held in place by a ring nut 54 and the charge 55 is likewise held in place by a disk 56. It is obvious from an inspection of the drawing and from 10 the foregoing description that the plate 53 may contain any number of caps 57 for it is desired to insure against defects in the operation of one or more igniting devices. For the purpose of illustrating the invention, however, the showing in Fig. 7 is believed to be sufficient, as one skilled in the 15 art will readily appreciate that these parts may be duplicated.

Within the casing 51 there is a spacing 20 sleeve 58 which has one end bearing against the cap plate 53 and the opposite end bearing against a cartridge holding plate 59. Between the cap plate 53 and the cartridge holding plate 59, there is a perforated guiding 25 tube 60 in which a projectile from the cartridge 61 will pass to the cap 57. The means for exploding the cartridge preferably comprises the structure heretofore described for exploding the caps of the fuse, 30 particularly shown in Figs. 1 and 2, and only a fragment of that mechanism is illustrated in connection with the delayed firing device, but it will be apparent that if the hammer 62 strikes the head 63 of the 35 firing pin, the said firing pin will strike the cartridge and explode the same, it being understood that the centrifugally operated guards 67 will be employed and operated in the manner heretofore described. The head 40 63 has a leaf spring 64, which leaf spring lies in a recess 65 of the head and the said spring is anchored or secured to one end of the casing as at 66. The action of this 45 spring is to force the head inwardly when the guards 67 move to release the head.

It will be seen that the wall of the casing tapers and the depth of the thread is graduated by being reduced in depth toward the thin end of the casing, this being for the 50 purpose of maintaining the strength of the wall of the casing uniform practically throughout its length.

In the modified construction shown in Figs. 11, 12, 13 and 14, the casing 68 and 55 housing 69 are of the construction heretofore described, but in the present embodiment of the invention, the guards 70 are slidable in the channel 71 formed in the housing and a conical spring 72 having a base of 60 a diameter approximately the diameter of the channel is applied to the channel with the base of the spring lying against the sleeve 73. The guards 70 have their outer faces provided with concavities 74, the walls 65 of which are tapered approximately to the

taper of the springs when compressed so that the said springs will nest in the concavities when the guards move radially. The guards have central apertures 75 to permit the air to escape therethrough and each concavity 70 furthermore constitutes a seat for the end 76 of the spring so that the spring is held in proper position while the guard is moving with relation to it. In this construction, the face plate 77 has a slot 78 therein and the 75 head 79 of the firing pin has a transversely disposed guiding pin 80 therein which travels in the slot of the pin 78 and in a slot formed in the housing. The guiding pin 80 is loosely applied to the head so that it may 80 be inserted or removed.

In Fig. 12, I show the firing pin after it has been released by the guards and when it has been moved by a spring 81 so that the spurs 82 are approximately in contact with 85 the disk 83 which guards the caps 84. The remainder of the fuse is of the construction heretofore described and further detailed description thereof will be unnecessary.

The number of firing pins increases the 90 efficiency of the fuse and guards against defects of the caps so that if one or more of the caps are not exploded, one or more of the other caps will be effective to fire the charge. By this means, caps from different localities 95 may be employed so that if the caps of one locality had been tampered with, those from other localities when employed in the manufacture of the fuse would produce the desired result. 100

I claim—

1. In a fuse, a casing, a housing therein having transversely disposed ways, guards in the ways, cups with relation to which the guards telescope, springs interposed between 105 the cups and the guards, said guards having openings therein for the passage of air, a firing pin slideable in the housing, the said firing pin having a head engaged by the guards to prevent movement of the firing pin, said guards being moved by centrifugal force to release the firing pin, means for imparting initial movement to the firing pin to prevent resetting of the guards, means for holding caps in front of the firing pin, and 110 means for operating the firing pin upon impact of a projectile. 115

2. In a fuse, a casing, a housing therein having transversely disposed ways, guards in the ways, cups with relation to which the 120 guards telescope, springs interposed between the cups and the guards, said guards having openings therein for the passage of air, a firing pin slideable in the housing, the said firing pin having a head engaged by the 125 guards to prevent movement of the firing pin, said guards being moved by centrifugal force to release the firing pin, means for imparting initial movement to the firing pin to prevent resetting of the guards, a plate 130

having seats for caps, a disk on the plate for holding the caps in place, means for holding the plate with the caps in position to be exploded by the firing pin, and means for operating the firing pin upon impact of a projectile.

3. In a fuse, a casing, a housing therein having radial channels, and an aperture at right angles thereto, a firing pin comprising a head, shank and body, a plate on the housing having an aperture in which the head of the firing pin is slidable, a spring interposed between the body of the firing pin and one wall of the housing, guards slidable in the channels, means for holding the guards nor-

mally in engagement with the head of the firing pin, said guards being movable by centrifugal force to release the firing pin, a plate having seats for caps, a disk on the plate for holding the caps in place, means for holding the plate with the caps in position to be exploded by the firing pin, and means for operating the firing pin upon impact of a projectile.

In testimony whereof, I affix my signature in the presence of two witnesses.

DOMINGO A. PISTORIO.
